UNITED STATES PATENT OFFICE.

WARREN V. JOHNSON, OF BLOOMSBURG, PENNSYLVANIA, ASSIGNOR TO AMERICAN CAR AND FOUNDRY COMPANY, OF ST. LOUIS, MISSOURI, A CORPORATION OF NEW JERSEY.

MINE-CAR.

1,199,794.

Specification of Letters Patent.

Patented Oct. 3, 1916.

Application filed August 4, 1916. Serial No. 113,127.

To all whom it may concern:

Be it known that I, WARREN V. JOHNSON, residing at Bloomsburg, Columbia county, Pennsylvania, and being a citizen of the 5 United States, have invented certain new and useful Improvements in Mine-Cars, of which the following is a full, clear, and exact description, such as will enable others skilled in the art to which it appertains to 10 make and to use the same, reference being had to the accompanying drawings, which illustrate the preferred form of the invention, though it is to be understood that the invention is not limited to the exact details 15 of construction shown and described, as it is obvious that various modifications thereof within the scope of the claims will occur to persons skilled in the art.

In said drawings: Figure 1 is a side elevational view of my improved mine car; Fig. 2 is an end view thereof; Fig. 3 is a view of the opposite end of the car; Fig. 4 is a plan view; Fig. 5 is a vertical sectional view, the section being taken on line 5-5 of 25 Fig. 2; and Fig. 6 is a similar view, the section being taken on line 6-6 of Fig. 3.

A mine car should be light, strong and durable, possessing inherent qualities of elasticity to adapt it to resist service shocks, 30 and it should be so fashioned that it can be readily repaired in such parts where repairs are most frequently required.

For the bituminous regions it has been found advisable to employ wood in cars, 35 particularly in mine cars, and the present invention contemplates the employment of wood flooring 1 extending through and beyond the body portion A to form end bumpers of a composite type comprising the portions of the floor which extend beyond the body coöperating with wood bumper blocks 2 and end bumper bands 3 of metal which fit over the ends of the floor and bumper blocks. With these coöperate draw bars 4 45 of strap formation which extend preferably from end to end of the car, resting on and being bolted removably to the central floor board as best shown in Fig. 4 of the drawings, the end portions of such draw bars being bent upwardly, as best shown in Fig. 1, to form a space intermediate the bumper

and said draw bar for the link-coupling used with this type of cars. Coöperating with the wood floor are side sheets 5, end sheets 6 and end doors 7, all of which are 55 preferably formed of thin corrugated sheet metal to provide sufficient strength and elasticity for service.

Extending across below the floor 1 and paralleling the side sheets 5, are shown 60 channel-shaped body bands 8 which are bolted to the flooring and riveted to the side sheets, thus establishing a removable connection between the body bands 8 and the flooring, and a permanent connection between the side sheets and said body bands.

Resting upon the floor 1, and within the side sheets 5, are pressed angle-shaped members 9 which extend substantially the length of the interior of the body portion of the car 70 and said angle members 9 are riveted to the side sheets 5 and body bands 8 by through rivets 9^a at convenient intervals throughout the length of the car body. The horizontal leg of this angle member 9 is secured by 75 bolts to the floor 1 as and for the purposes hereinafter described.

Paralleling the corrugations of the side sheet 5 in the preferred construction, I provide relatively narrow corrugated bands 10 80 which reinforce the metal of said sheet 5 in proximity to the body bands 8 and rivets 10^a pass through the sheets 5, corrugated bands 10 and body bands 8. It is obvious that the corrugated sheets may be flattened 85 within the zones of the body bands 8, if desired, though this calls for an additional operation and an expense which is not necessary.

The fixed end sheet 6 extends outwardly 90 beyond the line of the side sheets 5, as best shown in Fig. 2, and laps the outstanding flanges 8^a of the end body band 8 at that end of the car body and said sheet 6 is secured thereto by rivets 6^a, as best shown in Fig. 95 2, said sheet extending downwardly to the floor to which it is connected through the bottom flange 6^b thereof, which, like the longitudinally extending angles 9, is preferably bolted to the wood floor. At the opposite 100 end of the car body is provided a dumping door comprising the sheet 7 of corrugated

- sheet steel which is hung on a roller bar 15 by door hinge straps 16. These straps are formed with looped upper ends which are mounted loosely upon the roller bar 15, being spaced by collars 15^a and sleeves 15^b on said bar and extend downwardly parallel with the door and are secured thereto by rivets extending through the door sheet and through the depending legs of said straps.
- 10 An eye-bolt 14 bolted to the floor 1 is provided with a link 14^a adapted to be looped over the staple 13 which in turn is riveted to the door 7, thereby enabling the end of the latch 11, bolted to the door and held on 15 the fulcrum strap 12, to pass through the loop 13 and secure the door in closed position.

The brake mechanism is of a conventional type modified to adapt it to the car forming 20 the present invention and comprises the brake ratchet arm 17 which is connected to the brake fulcrum 20 with a connection pin. The brake fulcrum is pivotally connected with the end sheet 6 and this connection allows the said fulcrum to equalize the pull on 25 the connection arms 21, which arms are connected to the brake ratchet arm 17 and brake beam arms 22 with suitable connection pins. The brake ratchet arm 17 is guided along 30 the brake ratchet 18 by brake ratchet arm guide 19 riveted to the end of the car body. The brake beam arms 22 extend along the sides of the car through guides 23 and are bolted to the brake block 24.

35 To reinforce the end sheet 6 for the brake manipulating mechanism just referred to, a reinforcing sheet 6^c may be provided which is secured to said end sheet 6 by suitable rivet connection thus distributing the stresses imposed upon said end sheet.

40 Coöoperating with the body portion may be any suitable gear, such as one comprising the cast iron journal boxes 27 which are held in line by the horizontal flange of the 45 angle 9, bolts 34 extending through the journal boxes, the car floor and said angle for this purpose.

45 It is obvious that the end body band to which the end sheet 6 is secured may be in 50 the form of an angle, if desired, though it is advisable that the channel section be employed as it forms a convenient rolled section of the approximate strength for the purpose required. Likewise various other 55 detail modifications within the skill of an engineer may be employed without departing from the spirit of the invention, which contemplates a light, strong and durable structure for the purposes specified, which 60 may be readily repaired and assembled and disassembled when required, and this by unskilled labor. To facilitate this the bolts 34, employed to hold the journal boxes 27 in position, pass through the horizontal flanges

of the angles 9, through the floor and through 65 the journal box, thereby tying together the journal boxes, floor and side sheet to hold the wheel assembly in proper alinement. The bolts 35 extend through the body bands 8, floor 1 and angle 9, thereby tying said 70 body bands, floor and angle securely and removably in position.

To stiffen and protect the upper edges of the side plates 5, said edges are inclosed within channels 40 which have elongated 75 flanges 41 resting between the top edge portion of side sheets 5 and the straps, in which position the rivets which secure the channel edge protecting strips 40 in position also connect the straps 10 with the side sheets 5. 80 Similarly the upper edge of the end wall 6 is strengthened and protected by the inverted U-shaped binding strip 42 which is held in position by rivets 43, as in the upper edge of door 7, wherein the inverted U-shaped binding is designated by numeral 46 and the rivets are denoted by 47. The lower edge of the door 7 is reinforced by a bottom edge plate 44 extending parallel therewith and secured thereto by rivets 45. 90

What I claim is:

1. In combination in a mine car, a wood floor portion, metallic body bands extending beneath said floor near its ends and intermediate its ends and secured directly to said floor, corrugated metal side body sheets secured directly to said body bands, flanged members connecting the side body sheets with said floor, longitudinally spaced journal boxes connected to each of said flanged members by bolts extending through said journal boxes, the floor and said flanged members, a fixed end wall and a hinged gate. 100

2. In combination in a mine car, a wood floor, a plurality of flanged body bands extending below and secured to said floor, corrugated side sheets secured to the webs of said body bands, an end sheet secured to a flange of one of said body bands, angle members resting on said floor and riveted to said side sheets and journal boxes bolted to said angle members and floor. 105

3. In combination in a mine car, a wood floor, a plurality of flanged body bands extending below and being secured to said floor intermediate the ends thereof, bumper blocks secured below said floor and abutting said body bands, side sheets riveted to said body bands, angle members riveted to said side sheets, journal boxes spaced longitudinally of said angle members, and bolts removably connecting said journal boxes, the floor and said angle members. 115

4. In combination in a mine car, a wood floor, flanged body bands extending therebelow along a plurality of lines intermediate the ends of said floor, bumper blocks secured to said floor near its opposite ends 125

and bearing against said body bands, a fixed end sheet riveted to a flange of one body band, a hinged gate at the opposite end of the body comprising a roller bar seated at 5 opposite ends in another body band, hinge straps hung on said roller bar, and a corrugated sheet secured to said straps.

In witness whereof I have hereunto set my hand in the presence of two witnesses.

WARREN V. JOHNSON.

Witnesses:
